PORTABLE GLUE SEALERS FOR CARTON BOTTOMS

Clarence Van Houdem King, Jr., Carmel, and John W. Margraf, Salinas, Calif., assignors to A. H. L. Klemme, East St. Louis, Ill.

Filed May 29, 1962, Ser. No. 198,501
8 Claims. (Cl. 93—44.1)

This invention relates to equipment which is used for the bottom sealing of carton flaps and particularly to a small machine using glue for the sealing, which is capable of being moved from place to place as required, both in the plant and out of the plant. The movement and portability of the machine does not entail the disassembly after use and the reassembly for use at the new location.

Heretofore the method of securing the bottom flaps of corrugated cartons has been by means of metal staples or stitchers. The various Federal and State laws and regulations pertaining to shipping cartons specify the number of staples required for a particular use and normally from six to twelve staples are required for even the most modest use. Such bottom closing of cartons becomes expensive and requires extra handling with the result that the carton expense prior to the time of packing is excessive.

Staples are dangerous because they loosen with use and upon loosening, or when they are incorrectly set, they expose sharp edges which cut the hands of the package handlers.

The machine of the present invention offers many advantages over the stitch closing of the carton bottom and one advantage is that it is considerably faster, requiring only one operation as against three or perhaps four, for the stitchers. Also, the sealed cartons cost is less in two particulars. In the first place, the glue used for sealing costs less than wire or staples and in the second place, the labor to accomplish the sealing is one-third to one-fourth that of the stitching operation. In addition, there is less upkeep to the machine of the present invention as compared with stitchers because breakdowns are less frequent and less involved. The machine of the present invention is much less complicated than stitchers, having less moving parts and less involved and critical motions. A very important advantage is that the glue sealed cartons are some twenty-seven percent stronger than stitched cartons.

It is recognized that there are extant machines for glue sealing carton bottoms but these are very large machines which require considerable floor space because of their length. Also, they are heavy pieces of equipment weighing not less than 1600 pounds.

The machine of the present invention weighs only some 400 pounds and can easily be moved by a fork lift or skidded behind a small tractor.

It is smaller in over-all dimensions having a height of only some 40 inches, a length of some 37 inches and a width of less than 40 inches. It is an all electric machine requiring no vacuum pump or compressor and therefore eliminates the troublesome matters attendant on air or vacuum lines and valves. It is apparent that the machine of the present invention costs only a fraction of the cost of the larger machines and therefore is economic for situations which could not possibly be served by the larger machines. Perhaps one of the greatest advantages lies in the fact that the machine of the present invention has a throughput capacity which is the equal of or greater than that of the very large machines. In addition, the repairs and upkeep are minimal with the machine of the present invention and requires practically no down time as compared with the specially built large machines currently in use.

2

A particular advantage of the present invention is that no take-off mechanism is required as all take-off of bottom sealed cartons is by gravity. In this manner a large amount of special equipment ancillary to the machine itself is eliminated.

Further objects are to provide a construction of maximum simplicity, economy and ease of assembly and disassembly, also such further objects, advantages and capabilities as will fully appear and as are inherently possessed by the device and invention described herein.

The invention further resides in the combination, construction and arrangement of parts illustrated in the accompanying drawings, and while there is shown therein a preferred embodiment thereof, it is to be understood that the same is illustrative of the invention and that the invention is capable of modification and change and comprehends other details of construction without departing from the spirit thereof or the scope of the appended claims.

In the drawings:

FIGURE 1 is a side elevational view of the lefthand side of the machine as gauged by the operator who stands to the right and faces to the left in FIGURE 1;

FIGURE 2 is an end elevational view of the machine looking from right to left in FIGURE 1 and is the view from the operator's end;

FIGURE 3 is a detail of the bottom side flap closing and holding means taken on the line III—III of FIGURE 1, looking in the direction of the arrows;

FIGURE 4 is a detail of the main cam;

FIGURE 5 is a fragmentary top plan view, partly in section, taken along the line V—V of FIGURE 4 and looking in the direction of the arrows;

FIGURE 6 is a detail of one of the carton mandrels partly in elevation and partly in section;

FIGURE 7 is a fragmentary detail of the mandrel and guide taken on the line VII—VII of FIGURE 6;

FIGURE 8 is a fragmentary diagrammatic illustration showing the gluing of the outer face of the carton end flaps and compensating for the difference in radius of the various portions of the carton bottom during this operation;

FIGURE 9 is similar to FIGURE 8 showing the maximum reduction in the radius by means of the main cam.

The machine of the present invention is for the bottom sealing of cartons and the like. Corrugated paper packing cartons having four walls, top side and end flaps and bottom side and end flaps are supplied by the manufacturer in flats, with the open corner suitably secured together. Just before use, the flat is opened to rectangular tubular form for presentation to the sealing machine. A carton is put on the mandrel of the machine in telescopic manner, with the top flaps first. The bottom end flaps are folded against and held on the machine and are rotated about a single axis and in the rotation of the box, the bottom end flaps are glued, the bottom side flaps are folded and then pressure-sealed.

The carton sealing machine of this invention is constructed with a pair of A frames generally designated 20. The A frames each have the usual cross stiffeners 21 which are placed on the outer surfaces so as not to interfere with the space between. The A frames 20 are spaced apart from each other and mounted on a base 22. At the apex of the pair of A frames 20, the main rotating shaft 23 is journaled as at 24. The shaft 23 represents the transverse rotating axis for the entire operation of the machine. Secured to the hub of the shaft 23 for rotation therewith are two oppositely disposed, radially extending arms 26, each set of four arms 26 carries an outwardly directed angle member 27. Fitted over in telescopic relation at the ends of each of these arms 26 is a carton mandrel 28. The carton mandrel is approximately

the same size and shape as the inner dimensions of the carton which are to be bottom sealed. The corners 30 of the top face (which corresponds with the bottom of the carton) are shaped angularly as at 30 to assist in the placement of the carton thereover in precise squareness and to secure the proper registration and positioning of the carton. It will also be observed that the outer face of the mandrel 28 has two transverse plates 31 and 31a which approximate the size and shape of the bottom end flaps of the carton. Adjacent each side of these outer plates 31 and 31a are spring loaded clips 32 which are adapted to engage the inner edge of the end flaps of the carton in a manner to be explained hereafter. Each mandrel is provided with four sets of wheels 33 which guide on the edge outwardly extending leg 27 of the L-shaped members 26 so that the mandrel will ride radially inwardly and outwardly on said wheels 33 in the track edges 27. Within the mandrel form, the mandrel is connected to a tension spring 34 which spring is attached to its other end to the main arm 26. Thus, when the mandrel moves inwardly on the tracks 26, the tension is relieved by compression against spring 34. Thus, when the compression is released the tension on spring 34 will pull the mandrel back to the radially extended position shown in FIGURE 6.

Also secured to the hub 25 for rotation with the shaft 23, are two cam follower arms 35 and 35a which are spaced exactly 180° from each other. The peculiar shape of the arm 35 is necessary so that it does not interfere in any way with the putting on or taking off of the carton, or any phase of its rotation in the machine. At the outer end of the arms 35 and 35a is mounted rotating cam follower wheels 36 and 36a respectively. The cam follower wheel 36 in each instance, engages the outer peripheral edge surface of the cam 37. Cam 37 is a stationary plate secured by bolts 38 or in any other suitable manner, to the two legs of one of the A frames 20. In this manner, the cam is held securely in position. The cam is cut with an internal grooved slot 40 so that it may be rotated slightly in a vertical plane in either direction to secure the proper timing relationship required for the machine's operation. This timing relationship is important because the cam 37 on its outer face is circular and concentric with the axis of the shaft 23, except in one instance. A hump is provided which commences at approximately 3 o'clock, reaches its maximum at substantially 4:30 and returns to the circular form at approximately 5:30. As will be explained later, the hump 41 on the outer peripheral surface of cam 37 controls the in-and-out movement of the mandrel 28 and the movement thereof on the wheels 33 guided by the tracks 27. It will be observed that each of the cam followers 36 and 36a will pass over the outwardly extending hump 41 of cam 37 once each revolution and exactly 180° out of phase with each other. Cam 37 is also provided with an inner face 43 against which the cam follower 44 is held in resilient engagement. Cam 44 is held in resilient, but offset engagement with respect to a timing bar locking means 45 which is attached to and rotates with the shaft 23. When the timing bar 45 in its rotation (which is clockwise with respect to FIGURE 1 and counter-clockwise with respect to FIGURE 4) reaches 40° from the horizontal center line 46 and at another point exactly 180° therefrom, the locking tip 47 will engage a locking catch 48. At the same time, the cam follower 44 will come to rest against a stop 50, since the machine is designed to rotate only one-half a turn at each step, the cam face 43 is provided with two such stops 50, 180° out of phase from each other, and two locking devices or catches 48. Thus, although the arm 45 rotates only once, it will be stopped and started twice during a single rotation. The spring 51 on the latch detent 48 is heavy enough so that the whole machine will be stopped positively at the end of each half rotation.

At the forward end of the base 22 and midway between the spaced A frame members 20, is a glue pot generally designated 52. The glue pot is substantially rectangularly

shaped and is resiliently mounted at each of its four corners on springs 53 in order to accommodate any irregularities of pressure or variations in the thickness of the corrugated board of the boxes. The glue pot has a false bottom 54 in which are mounted heating elements 55 and these in turn are connected through electric terminals to a source of electric power for purposes of keeping the glue hot. Because of the necessity of keeping the glue at a constant temperature, a thermostat (not shown) may be included in the circuit. Also, the glue pot 52 has suitably insulated sides and bottoms as at 57 to help keep the glue therein at constant temperature. Under certain conditions it is only necessary to mount the glue pot resiliently as at 53 at its outer end (see FIGURE 1). In this manner, the expansion spring tends to keep the outer end of the glue pot elevated for reasons which will become apparent later on. Mounted transversely in the glue pot with a substantial portion thereof exposed above its top, is a glue roll 58. This is the usual cylindrical form and rotates on the stub shaft 60 which is journaled in the sides of the glue pot 52 as at 61. Carried on the outer end of the shaft 60 adjacent one of the outer sides of the glue pot 52, is a drive sprocket 61a. It is apparent that as the glue roll 58 rotates in a clockwise direction (see FIGURES 8 and 9), it picks up glue on its outer surface.

The drive for the machine is as follows: motor 62 drives to a larger pulley 63. On the shaft 64 rotated by the pulley 63, is a small sprocket 65. Chain 66 drives a large sprocket 67 which is mounted for rotation on the shaft 68. Shaft 68 has a small sprocket 70 mounted for rotation therewith at the opposite end and just inside one of the A frame members 20. A small sprocket 70 and chain 71 drive a larger sprocket keyed to the shaft 23 which sprocket 72 rotates the shaft 23, and by this means rotates the whole moving equipment. The chain 66 passes over sprocket 73 to drive it in the opposite direction and rotate the shaft 74. Shaft 74 has mounted for rotation with it, the small sprocket 75 which through chain 76 rotates the sprocket 77 which is keyed to the shaft 60 journaled in the glue pot 52 to rotate the glue roller 58. Since the motor 62 rotates continuously, all of the chains and gears move continuously with the exception of sprocket 70, chain 71 and sprocket 72. The gear or sprocket 70 is coupled to a clutch mechanism (not shown) so that when the foot treadle is pressed by the operator the clutch engages and causes the sprocket 70 to rotate one-half turn and then shut off. This causes the shaft 23 to rotate one-half turn and all of the mechanism carried by the shaft. The shut-off corresponds with the time and location of the locking bar 45 when it is stopped by the latch detent 48 simultaneously with the cam follower 44 meeting the stop 50.

Adjustably attached at each end of the shaft 23 on the outside of the A frame members are a pair of irregularly shaped cams 80. The cams 80 are secured on the shaft 23 for rotation therewith by mounting couplings 78. Secured to the front legs of each A frame as at 81 is a bracket 82 which pivotally mounts a bell crank member 83, which member pivots about the pivot pier 84. At the outer apex or elbow of the bell crank 83 is a rotating cam follower 85 which bears against the peripheral irregular surface of the cam 80. Secured to the other leg of the bell crank 83 is a piston 86. The piston 86 reciprocates in response to the action and movement of the cam follower in following its travel around the peripheral edge of the cam 80. On the rearward legs of each A frame is another bracket 87 which is secured thereto in any suitable manner. This bracket 87 carries a pivoting stub shaft 88. A Y-shaped pressure element 90 carrying a pair of pressure pads 91 at the extremities of the Y, is mounted for pivotal rotation with the stub shaft 88. The Y-shaped pressure frame has an extension at its upper end for lapped rotating engagement with the piston 86. This extension is 92. In the stopped position, which is in the northeast quadrant 40° above the horizontal 46, the

Y-shaped pressure element 90 is in open position and the piston rod 86 is directly axially aligned with the stopping point so that the position shown in FIGURE 1 is the loading position.

It will be observed that as the cam 80 rotates, the cam follower 85 is depressed, causing the piston to move angularly downward, as shown in the broken lines of FIGURE 3, pivoting the Y-pressure members 90 inwardly on their respective pivots 88 toward each other, and to move upwardly in an arc of substantially 90°.

Operation

The operation of the device is substantially as follows: although not shown in FIGURE 1, the starting position is actually the angular axis indicated by the line 95 in the northeast quadrant above the horizontal axis 46 where the outline of the mandrel is shown in broken lines. The mandrel 28 is presented at an angle in this starting position so that the operator can open the four-sided carton 100 and easily slip over the same onto the mandrel in a very quick and simple movement. Cartons are supplied by the manufacturer in flats as before stated. The cartons 100 have top side flaps 101 and top end flaps 102 as well as bottom side flaps 103 and bottom end flaps 104. The operator opens the flats to substantially rectangular tubular position and slips this tube telescopically over the mandrel with the side and end top flaps first. The mandrel 28 brings the carton into properly squared position. As indicated before, the cut-off corners 30 on the top plates of the mandrel prevent any catching of the box on the corners, speed the telescoping of the carton over the mandrel, and assist in the squaring of the same on the mandrel. In the same movement that the operator places the carton telescopically over the mandrel 28, he folds down the bottom end flaps 104 of the carton 100 onto the pads 31 and 31a so that the inner edges of the end flaps engage the locking means 32a to hold them flat against the plate. When this is complete, the operator presses the foot treadle (not shown) and the arms 26 begin their rotation clockwise as viewed in FIGURE 1. It is to be remembered that all of the cam followers and cams begin to function as soon as the machine is started and the clutch engages the sprocket 70 to start the rotation. It is obviously necessary for the glue roller 58 to contact the bottom end flaps 104 of the carton 100 in order to apply a film of glue thereto. Contact must be maintained with some pressure and continuously. The flat outer surface of the mandrel with the end flaps flat against it travel in an arc with the face at its center point at a tangent to the arc of rotation and the bottom side flaps 103 pass in a substantially vertical plane at either side of the gluing pot 52. Accordingly, the radius to the corners is greater than the radius at the center. Thus, if the pressure of the roll was set for the radius which is sufficient to let the corners pass, obviously there would be no glue applied except at a small portion of the entering edge and a small portion adjacent the trailing edge. Thus, the travel of the carton on the mandrel has to adjust for the difference in radius. As the leading corner of the carton approaches the glue roller 58, the cam follower 36 (or 36a) encounters the beginning of the hump 41 on the cam 37. This forces the mandrel to move upwardly on its tracks 26 and roller 32, to relax the spring 34 and to make the radius equal to the radius at the tangent. Thus, all of the front or leading bottom end flap 104 of the carton 100 is contacted by the face of the glue roller 58. The hold-down clips 32a, of course, are spaced outwardly to a point so that they do not interfere with the action of the gluing by the roller 58. As the movement continues, the cam follower 36 (or 36a) reaches the summit of the hump 41 on the cam 37 which of course represents the minimum radius or the radius at the tangent, i.e., the radius at the center line. As the trailing bottom end flap 104 of the carton 100 presents itself to the gluing, the radius has again to be reduced and this is done by the cam follower

36 traveling down the opposite side of the hump 41 where the spring 34 takes over and pulls the mandrel back to its extended position.

Just after the gluing of the trailing bottom end flap 104, it will be observed that the cams 80 and the pistons 86 are substantially in the open position shown in FIGURE 1. As the cam follower 85 traveling on the perimeter of cam 80 is depressed by the rotation of the cam 80, the piston 86 is also moved axially downward along the line defined by numeral 95, causing the pads 91 to engage the bottom side flaps 103 and fold them into position against the glued faces of the bottom end flaps 104. When the machine reaches the position defined by the line 95, having completed 180° of rotation, the clutch cuts out the power which stops the rotation and simultaneously the latch member 47 on arm 45 engages the appropriate latching detent 48. At this time, the pads 91 are in full pressure against the bottom flaps causing the locking means 32a on the mandrel top plate to disengage so that the sealed box is held on to the mandrel only by the pressure pads 91. Sufficient residence time is provided to allow the glue to set before starting the second 180° rotation. This time is usually provided by the length of time it takes an operator to secure a carton flat, open it and telescopically slip it over the mandrel. The moment the treadle is pressed by the operator to engage the power and clutch mechanism the 180° cycle is repeated to complete the 360° rotation. Thus, two boxes are bottom glue sealed with every complete rotation. It should be stated that as a cycle is started the cam 80 rotates to cause the Y-shaped holding means to release immediately and permit the bottom sealed carton to fall freely from the mandrel.

We claim:

1. Apparatus for receiving a partially completed paper carton having the four sides thereof connected to form the rectangular body portion, each of said sides having connected thereto along substantially the length and width thereof closable top and bottom side and end flaps, said apparatus comprising a beam rotatably supported on a shaft located at right angles thereto and substantially at the midpoint thereof, each of the two ends of said beam having mounted thereon box supporting means for receiving therearound said rectangular body portion of said carton in a position such that two sides of said body portion define vertical planes and for thereafter preventing the bottom carton flaps, farthest from said horizontal shaft, from being folded inwardly beyond their positions of normal closure, a stationary container for liquid adhesive having an associated adhesive applicator so located that upon rotation of said beam with said carton when the two bottom end flaps are maintained in approximately the position of normal closure said applicator will contact the external surfaces of said flaps and accommodate to the various radii, means for rotating said beam, means for maintaining said bottom end flaps in approximately the position of normal closure at least until contact with said applicator, offset reciprocal means at either side of the plane of rotation for folding the remaining two bottom side flaps over and into contact with the two glued bottom end flaps, and means for supporting said beam supporting horizontal shaft.

2. Apparatus for receiving a partially completed paper carton having the four sides thereof connected to form the rectangular body portion, each of said sides having connected thereto along substantially the length and width thereof closable top and bottom side and end flaps, said apparatus comprising a beam rotatably supported on a shaft located at right angles thereto and substantially at the midpoint thereof, each of the two ends of said beam having mounted thereon box supporting means for receiving therearound said rectangular body portion of said carton in a position such that two sides of said body portion define vertical planes and for thereafter preventing the bottom carton flaps, farthest from said horizontal shaft, from being folded inwardly beyond their positions

of normal closure, means for mounting said box supporting means on said beam for limited axial movement, a stationary container for liquid adhesive having an associated adhesive applicator so located that upon rotation of said beam with said carton when the two bottom end flaps are maintained in approximately the position of normal closure said applicator will contact the external surfaces of said flaps, means for rotating said beam, means responsive to the rotation of said beam for moving the box supporting means axially inward and outward, means for maintaining said bottom end flaps in approximately the position of normal closure at least until contact with said applicator, offset reciprocal means at either side of the plane of rotation for folding the remaining two bottom side flaps over and into contact with the two glued bottom end flaps, and means for supporting said beam-supporting horizontal shaft.

3. Apparatus for receiving a partially completed paper carton having the four sides thereof connected to form the rectangular body portion, each of said sides having connected thereto along substantially the length and width thereof closable top and bottom side and end flaps, said apparatus comprising a beam rotatably supported on a shaft located at right angles thereto and substantially at the midpoint thereof, each of the two ends of said beam having mounted thereon box supporting means for receiving therearound said rectangular body portion of said carton in a position such that two sides of said body portion define vertical planes and for thereafter preventing the bottom carton flaps, farthest from said horizontal shaft, from being folded inwardly beyond their positions of normal closure, a stationary container for liquid adhesive having an associated adhesive applicator so located that upon rotation of said beam with said carton when the two bottom end flaps are maintained in approximately the position of normal closure said applicator will contact the external surfaces of said flaps, means for rotating said beam in cycles of 180°, means responsive to the rotation of said beam in said cycle for moving the box supporting means axially inward and outward, means for maintaining said bottom end flaps in approximately the position of normal closure at least until contact with said applicator, offset reciprocal means at either side of the plane of rotation for folding the remaining two bottom side flaps over and into contact with the two glued bottom end flaps and holding pressure thereon at the end of each cycle until the adhesive is set and the bottom secured, and means for supporting said beam-supporting horizontal shaft.

4. A portable flap closing and sealing machine for a carton having four body panels all joined together, and having integral top and bottom side and end flaps, comprising in combination a pair of spaced side-by-side frame members secured to a base, a substantially horizontal shaft journaled transversely between said frame members, arms extending radially from said shaft and oppositely mounted thereon for symmetrical rotation in a vertical plane between said frame members, an element mounted at each end of said arms for receiving a carton thereon in telescopic relation, with the bottom side and end flaps projecting radially outward from the outer flat face of said element, means associated with said element for releasably holding the bottom end flaps against the outer flat face of said element, power operated means for effecting a 180° rotation cycle of said arms to a stop, a gluing mechanism disposed in the path of rotation of said elements, said gluing mechanism being yieldably mounted with a glue roller for contacting the outer faces of the end flaps of said carton adjusting to the various radii as it is moved past, releasing offset pressure means at either side of the plane of rotation reciprocally synchronized with the 180° rotation to engage the bottom side flaps of said carton, fold them against the glued surfaces of the end flaps and hold them with sufficient pressure until the glue sets and then to release.

5. A portable flap closing and sealing machine for a carton having four body panels all joined together, and having integral top and bottom side and end flaps, comprising in combination, a pair of spaced side-by-side frame members secured to a base, a substantially horizontal shaft journaled transversely between said frame members, arms extending radially from said shaft and oppositely mounted thereon for symmetrical rotation in a vertical plane between said frame members, a mandrel mounted at each end of said arms for receiving a carton thereon in telescopic relation, with the bottom side and end flaps projecting radially outward from the outer flat face of said mandrel, means associated with said mandrel for releasably holding the bottom end flaps against the outer flat face of said mandrel, power operated means for effecting a 180° rotation cycle of said arms to a stop, a gluing mechanism disposed in the path of rotation of said mandrel, said gluing mechanism being yieldably mounted with a glue roller for contacting the outer faces of the end flaps of said carton adjusting to the various radii as it is moved past, releasing offset pressure means at either side of the plane of rotation reciprocally synchronized with the 180° rotation to engage the bottom side flaps of said carton, fold them against the glued surfaces of the end flaps and hold them against the outer surface of said mandrel at the conclusion of the 180° rotation, and means releasing and clearing the pressure means at the start of the next cycle of 180° rotation to permit the bottom sealed carton to be released from the mandrel of the machine.

6. A portable flap closing and sealing machine for a carton having four body panels all joined together, and having integral top and bottom side and end flaps, comprising in combination, a pair of spaced side-by-side frame members secured to a base, a substantially horizontal shaft journaled transversely between said frame members, arms extending radially from said shaft and oppositely mounted thereon for symmetrical rotation in a vertical plane between said frame members, a mandrel mounted at each end of said arms for limited radial movement axially with respect to said arms for receiving a carton thereon in telescopic relation, with the bottom side and end flaps projecting radially outward from the outer flat face of said mandrel, means associated with said mandrel for releasably holding the bottom end flaps against the outer flat face of said mandrel, power operated means for effecting a 180° rotation cycle of said arms to a stop, a gluing mechanism disposed in the path of rotation of said mandrel, said gluing mechanism being yieldably mounted with a glue roller for contacting the outer faces of the end flaps of said carton as it is moved past, means associated with the rotation cycle means for moving the mandrel inwardly and outwardly to maintain the proper radii for the application of the glue on the said bottom end flaps, releasing pressure means synchronized with the 180° rotation to engage the bottom side flaps of said carton, fold them against the glued surfaces of the end flaps and hold them against the outer surface of said mandrel at the conclusion of the 180° rotation, and means releasing and clearing the pressure means at the start of the next cycle of 180° rotation to permit the bottom sealed carton to be released from the mandrel of the machine.

7. A portable flap closing and sealing machine as set forth in claim 6, further characterized in that the glue applying means is provided with a yieldable mounting and is biased to its projected position so that the glue is applied to the bottom end flaps under slight pressure.

8. The method of sealing bottom flaps of a carton comprising the steps of placing an opened carton flat with its two side and two end flaps at top and bottom lying in the planes of their common sides and ends but with the bottom flaps outward, over a carton supporting member said carton supporting member corresponding with the rectangular shape of the carton, holding the two bottom end flaps of said carton against the outer peripheral

face of said supporting member while rotating the same, presenting the folded bottom end flaps during said rotation to a glue applicator for applying glue to the exposed surface of said bottom end flaps, varying the radius of the carton supporting member during rotation to secure the application of glue over most of the surface of said bottom end flaps, folding said bottom side flaps toward the glued surfaces during rotation and externally supporting the carton on said supporting member during such travel, pressing the folded bottom side flaps against the glued areas of the bottom end flaps during a dwell in the

10

rotation to seal the same together with the carton supporting member maintaining the precise rectangular shape of the carton, resuming the rotation to release the pressure from the bottom sealed carton, and delivering the same ready for packing.
